UNITED STATES PATENT OFFICE.

CHARLES S. ASH, OF GENEVA, NEW YORK.

TRUING-STAND.

1,353,505.

Specification of Letters Patent. Patented Sept. 21, 1920.

Application filed August 10, 1918. Serial No. 249,281.

To all whom it may concern:

Be it known that I, CHARLES S. ASH, a citizen of the United States, residing at Geneva, in the county of Ontario and State 5 of New York, have invented certain new and useful Improvements in Truing-Stands, of which the following is a full, clear, and exact description, such as will enable others skilled in the art to which it appertains to 10 make and use the same.

This invention relates to improved apparatus for use in the manufacture of wire spoked vehicle wheels and is directed more particularly to an improved device whereby the hubs and rims of such wheels may 15 be expeditiously assembled and held while the series of interconnecting spokes are attached therebetween.

One of the objects of the invention is to 20 provide simple, reliable and efficient apparatus for the purpose mentioned which is easy to operate and not likely to get out of order.

It is another object to provide a functionally 25 advantageous and structurally desirable device whereby the hubs and rims of such wheels, or other suitable elements, may be accurately positioned and held in concentric relation during further operation thereon 30 in course of manufacture or repair.

Certain of the additional objects and advantages will be in part mentioned hereinafter in connection with the following 35 description of the accompanying drawings, which illustrate typical embodiments of the invention, and in which—

Figure 1 is a side view, half in elevation and half in cross section, of the improved apparatus (with certain parts omitted);

Fig. 2 is a sectional view on the line X—X of Fig. 1;

Fig. 3 is a top plan view of one-half of a table element in the device;

Fig. 4 is a half sectional view of parts 45 shown in Fig. 1, but enlarged; and

Fig. 5 is a similar view of a modified form of device.

It has heretofore been customary, in the manufacture of wire spoked wheels, to assemble 50 the hub shell and tire-carrying rim in only approximately concentric relationship and then to lace the spokes therebetween and tighten the same by a power-driven turning tool, in the nature of a screw-driver, which is applied to the nipples seating 55 in the rim and screwing on the spokes.

In such practice the screw-driver may have a slip drive connection whereby the tensioning of various spokes is automatically rendered approximately uniform. Assembly in 60 this manner, however, has required a subsequent operation of truing, in which the rims are further tested for concentricity with respect to the hub and additional labor expended in manually adjusting the spoke 65 nipples around the circumference of the rim to effect more exact uniformity of tension and also accurate centering of the hub.

The present invention comprises, in general, apparatus whereby the hub shells and 70 rims may be initially positioned in true concentric and lateral relationship and firmly maintained so during the operation of interconnecting the spokes therebetween. By the use of such apparatus, manufacture is 75 expedited and the cost decreased, since the subsequent truing step becomes a matter rather of precautionary inspection than of actual manufacturing necessity with attendant time and labor expense.

Referring more specifically to the drawings, there is shown in Fig. 1 apparatus including a pedestal 1, a rotatable table 2 journaled thereon and having a plurality of radially disposed and symmetrically arranged clamping jaws 3 adapted to grip the wheel rim about its outer periphery, and a central spindle or axial support 4 journalled in the pedestal and having means releasably to grip a hub shell concentric with respect 80 to the rim.

The table 2 is built up of several parts, between certain of which there is relative movement for purposes to be described, and includes a circular body plate 5 having a 95 plurality (in this instance eighteen) of symmetrically arranged radial slots or guideways 6 and having a circular groove or channel 7 in its bottom face. An annular member 8 is provided to fit within the channel 7 and on its upper face has relatively large spiral threads 9 projecting into the guideways 6. Plate 5 and disk 8 are carried on a supporting plate 10 rigidly secured to the former by bolts 11 and rotatably supporting the latter by an underhanging portion 12 which fits in channel 7 against the lower and inner surface of the member 8. The clamping jaws 3, for convenience of manufacture, may comprise a body element 110 13 shaped as shown in Fig. 2 to fit within the guideways 6 for radial movement with

respect to the plate 5 and the clamping jaws proper, 3, secured to the elements 13 by countersunk screw bolts 14. The members 13 are further provided with spiral threads 5 9' complementary to and fitting in the spiral threads 9 of disk 8.

The table as a whole is rotatably mounted on a tubular extension 15 of the pedestal 1. For this purpose the extension 15, intermediate its length, is provided with a tapered portion 16 having an outer conical bearing surface to receive a complementary bearing surface 17 of supporting plate 10. Above the surface 17 mentioned, plate 10 15 is also provided with a reversely tapered bearing surface 18, and a holding collar 19 is threaded interiorly to screw on the upper threaded end of pedestal member 15 and is provided at its lower end with a tapered 20 bearing surface complementary to and adapted to rest against bearing surface 18. One or more retaining nuts 20 thread on the extension 15 to hold the collar 19 against turning. 25 By the construction thus described, the entire table 2 is rotatable on the center pedestal, and the bearing surfaces thereof are such that any slight wear thereon incident to use is compensated by relative vertical 30 movement without disturbing the true concentric relationship of the parts.

Within the pedestal extension 15, and also rotatably supported thereby, is arranged the spindle 4. For this purpose the latter is 35 provided at its lower end with a head 21 which may support a bearing element 22 in turn seating against a complementary shoulder on the inside of the tapered portion 16, while intermediate its ends the spindle is 40 provided with threads 23 on which one or more retaining nuts 24 screw and abut friction washers 25 disposed in a shouldered recess 26 at the upper end of the member 15. The spindle 4 immediately above the threads 45 23 is contracted in diameter to afford a shoulder 27.

In use, the table 2 is designed to receive a wheel rim (indicated at 28 in dotted lines on Fig. 1) and to hold the same securely 50 clamped by the jaws 3 in centered or axially alined relationship to the spindle 4. The spindle in turn is designed to carry a wheel hub (indicated in dotted lines in Fig. 1), and for this purpose a lower hub-holding 55 element or collar 30 fits over spindle 4 and abuts shoulder 27. Upon positioning of the hub 29 thereover an upper hub collar 31 also fits on the spindle and, by means of a removable tapered key 32 fitting through 60 a slot in the spindle, the hub collars 30 and 31 may be driven together to firmly clamp the hub 29 therebetween in true concentric relation with the spindle and therefore with the rim 28. Due to the capability of free 65 rotation of the spindle 4 and to the inde-

pendent rotation of the table 2, it will thus be noted that the rim 28 and hub 29 may be quickly assembled on the device in concentric relation, and in horizontal planes as desired to effect the requisite degree of offsetting of the hub when the spokes are laced between the wheel parts. To facilitate mounting the rims 28, the plate 8 is provided at its rim with a handle 33 whereby, when body plate 5 is held against rotation, 70 for example by manually gripping one of the jaws 3, the plate 8 may be rotated, and, due to the spiral threads 9 and 9', jaws 3 are all moved in or out synchronously to grip or release the rim. When gripped, the whole 80 table 2 and the rim are free to rotate together on the bearings 17 and 18 as described.

Since it is most important to insure concentricity of the hub and rim when assembled, the construction of bearings for the plate 10 and the spindle 4, as described, is particularly advantageous in that relative wear thereof may be easily taken up in a vertical direction without disturbing the 90 alined relationship of all of the parts carried on the pedestal. 85

The various bearings are, of course, arranged for lubrication, and in the devices shown this is accomplished by means of an oil well 34 in the side of collar 19 to receive oil through a passage 35 drilled in plate 5. Likewise the recess 26 in the upper end of element 15 may be sufficiently large to provide an oil channel above the friction washers 25. 95

The pedestal 1, in the embodiment shown, is threaded on a taper at its upper end to receive the threads of extension 15 and a locking ring 36. It will be understood, however, 105 that this particular assembly is preferred for reasons of manufacturing economy and convenience and that other structures would be possible within the scope of the invention, in which the concentric assembly and relationship of the rotatable spindle 4 and table 2 would be secured. It will of course also be understood that the guideways 6 and jaws 3 are symmetrically disposed around the table: Certain of these have been omitted from Fig. 110 1 for clearness of illustration. 115

In Fig. 5 a somewhat modified embodiment of the invention is illustrated, having, however, the same general construction and operation. In this instance, however, the 120 table 2 is mounted to rotate on ball, or other friction reducing, bearings 37 positioned between a shoulder 38 on member 15' and a shoulder 39 on plate 10. Further, in this modification, the pedestal extension 15' is 125 internally threaded at its upper end to receive an externally threaded tubular element 40 having at its lower end a conical or tapered bearing 41 against which fits the head 21 of the spindle 4. Member 40, in this in- 130

stance, is provided with a recess 42 at its upper end to receive the friction washers 25 and retaining nuts 24 and is locked by a jam nut 43. In the construction of Fig. 5 it will be noted that the threaded engagement of the member 40 and the extension 15' permits a vertical adjustment of the spindle 4 with respect to the table 2, whereby any relative vertical wear between these parts 10 may be compensated or whereby the elevation of the hub holders 30, 31 may be altered as desired to change the degree of offsetting of the hub 29.

In both devices, however, the table 2 allows a rapid mounting of the rims 28 in firm centered relation and a likewise rapid mounting of the hubs 29 on spindle 4. As these parts are thus secured in true concentricity and correct transverse planes, the operation 20 of interlacing the wire spokes between the rim and hub may be quickly accomplished. Due to the independent rotation of the spindle and table, furthermore, the hub and rim will readily assume a correct rotary adjustment as the spokes are tensioned therebetween, so that with the device a complete and finished spoke lacing is accomplished by the operator as a single step in the manufacture; that is to say, as mentioned hereinbefore, the 30 hub and rim are firmly maintained in true concentricity so that a further manufacturing step of truing may be eliminated or becomes, at most, a matter of inspection rather than of skilled labor.

35 As many changes could be made in the above construction and many apparently widely different embodiments of this invention could be made without departing from the scope thereof, it is intended that all matter contained in the above description or 40 shown in the accompanying drawings shall be interpreted as illustrative and not in a limiting sense.

Having described my invention, what I 45 claim as new and desire to secure by Letters Patent is:

1. In a device for concentrically holding a wheel hub and rim, in combination, a rotatable support having a plurality of symmetrically arranged clamping jaws to grip 50 a wheel rim, and an axial support rotatable independently of said first mentioned support and having means to grip the wheel hub.

55 2. In a device for concentrically holding a wheel hub and rim while wire spokes are interconnected therebetween, in combination, a rotatable support and a plurality of clamping jaws operable jointly to grip a wheel 60 rim, and an axial support rotatable independently of said first mentioned support and having means to releasably grip the wheel hub.

65 3. In a device for concentrically holding a wheel hub and rim while wire spokes are

interconnected therebetween, in combination, a rotatable support having a plurality of symmetrically arranged clamping jaws to grip a wheel rim, and an axial support rotatable independently of said first mentioned support and having means to grip the wheel hub, both of said supports having bearing surfaces arranged concentrically whereby the concentricity of the gripping elements for the rim and hub is maintained in spite of 75 wear of said bearing surfaces.

4. In a device for concentrically holding a wheel hub and rim while wire spokes are interconnected therebetween, in combination, a rotatable support having a plurality of 80 symmetrically arranged clamping jaws to grip a wheel rim, and an axial support rotatable independently of said first mentioned support and having means to grip the wheel hub, both of said supports having bearing 85 surfaces arranged concentrically and against a common member whereby the concentricity of the gripping elements of the rim and hub is independent of the wear on said bearing surfaces.

90 5. In apparatus of the character described, in combination, a supporting standard, a rotatable table journaled thereon and having a plurality of clamping jaws constructed and arranged for synchronous movement radial to said table and rotary movement with said table, and a central spindle journaled on said standard and rotatable independently of said table, said spindle having means to center and releasably to grip a wheel hub 100 thereon.

6. In apparatus of the character described, in combination, a supporting standard, a rotatable table journaled thereon and having a plurality of clamping jaws constructed 105 and arranged for synchronous movement radial to said table and rotary movement with said table, a central spindle journaled on said standard and rotatable independently of said table, said spindle having means to center and releasably to grip a wheel hub 110 thereon, and means whereby said table and spindle may be relatively adjusted vertically.

7. In apparatus of the character described, in combination, a supporting standard, a 115 rotatable table journaled thereon and having a plurality of clamping jaws constructed and arranged for synchronous movement radial to said table and rotary movement with said table, a central spindle journaled on 120 said standard and rotatable independently of said table, said spindle having means to center and releasably to grip a wheel hub thereon, and means whereby said spindle may be adjusted vertically with respect to 125 said table.

8. In apparatus of the character described, in combination, a supporting standard, a rotatable table journaled thereon, clamping jaws supported at intervals on and radial to 130

said table, connecting means between said table and said jaws whereby rotation of one with respect to the other is permitted and effects relative radial movement of said jaws, 5 and a central support to releasably grip a wheel hub and permit rotation of the latter with respect to said jaws.

9. In apparatus of the character described, in combination, a supporting standard, a 10 rotatable table journaled thereon, clamping jaws arranged at intervals radial to said table, connecting means comprising interfit-

ting spiral threads between said table and said jaws whereby rotation of one with respect to the other is permitted and effects 15 relative radial movement of said jaws, and a central support to releasably grip a wheel hub.

In testimony whereof I affix my signature, in the presence of two witnesses.

CHARLES S. ASH.
